(57) **CLAIM**

I claim the ornamental design for a multi-orientable wall mountable air purifier, as shown and described.

DESCRIPTION

FIG. 1 is a rear perspective view of a multi-orientable wall mountable air purifier.

FIG. 2 is a front perspective view of the multi-orientable wall mountable air purifier.

FIG. 3 is a rear view of the multi-orientable wall mountable air purifier.

FIG. 4 is a front view of the multi-orientable wall mountable air purifier.

FIG. 5 is a left-side view of the multi-orientable wall mountable air purifier. The right-side view is a mirror image of the left-side view; and,

FIG. 6 is a top view of the multi-orientable wall mountable air purifier.

The broken lines illustrate portions of the multi-orientable wall mountable air purifier and form no part of the claimed design.
